PROTECTIVE RECEPTACLE

Charles F. Meilink, Toledo, Ohio

Application May 17, 1934, Serial No. 726,079

8 Claims. (Cl. 70—62)

This invention relates to receptacle protection against unauthorized access.

This invention has utility when incorporated in safe cabinets or other strong box constructions wherein there is an electrically controlled, time delayed, automatic unlocking.

Referring to the drawings:

Fig. 1 is a front view of an embodiment of the invention in a protective structure of a safe type, say for use in a bank or other place of business;

Fig. 2 is a fragmentary view on the line II—II, Fig. 1;

Fig. 3 is a section on the line III—III, Fig. 1;

Fig. 4 is a section on the line IV—IV, Fig. 3;

Fig. 5 is a section on the line V—V, Fig. 1;

Fig. 6 is a view of a throw-in switch and combination lock operator therefor from the inside of the jamb;

Fig. 7 is a wiring diagram of the electrical control features;

Fig. 8 is a detail view of the time delay device;

Fig. 9 is a fragmentary vertical section through the device as provided with auxiliary chambers;

Fig. 10 is a section on the line X—X, Fig. 9;

Fig. 11 is a front view of a square door type of safe embodying features of the invention;

Fig. 12 is a view of the inner side of the door for the safe of Fig. 11;

Fig. 13 is a section on the line XIII—XIII, Fig. 30 12; and

Fig. 14 is a fragmentary view of the door showing the key type of rotary lock instead of the combination lock of Fig. 11.

A general housing is provided having outer wall 1, inner wall 2 of sheet metal with insulation filler 3 therebetween. There is thus provided primary main chamber 4 having inclined bottom 5 from front opening 6 in the housing. This front opening 6 has jamb 7 as a door frame of armored steel. In this jamb 7 is opening 8 for circular closure or door 9.

On this jamb or plate 7 brackets 10 provide mounting for pin 11 as a hinge axis for brackets 12, 13, mounting the door 9. This door 9 has rigid therewith grip or handle 14. Into the chamber 4 is upper opening 15 to vestibule 16. Herein is unit inner wall structure 17 having front plate 18 with opening 19 therein. Pivot pins 20 in this opening 19 mount chute 21 having closure face 22 flush with the outer wall of the front plate 18. This portion 22 has handle or lug 23 which may be swung downwardly about the axis 20 to bring the chute 21 in position to receive coin or other matter and as this lug 23 is released the chute will swing downwardly and thus direct the deposit

from the way 16 through the opening 15 to lodge upon the inclined bottom 5 of the chamber 4. In the general assembly there is weld anchoring of the elements. However, the preliminary assembly of this chute device may be by bolts 24, 25. In addition to or in lieu of this chute device there may be slot 26 having protective teeth inner shield 27 so that, say paper deposits may be thrust thereinto for lodging on the inclined bottom of the chamber 4.

From this opening 15 there may be inclined partition section 28 (Fig. 9) to vertical partition section 29 having therein door 30 mounted by hinges 31. This door 30 is shown provided with lock 32 operable by key 33 for swinging away 15 from primary chamber 34 into auxiliary chamber 35 toward the opening 8. It is thus seen that in open position of the door 30 there is precluded access to the chamber 36 below the mat 37 resting on false floor 38. This false floor 38 has removable floor section or door 39 which may be anchored against removal by lock 40 to be released by operation of key through opening 41 when the mat 37 is removed from this vestibule.

The door 9 has assembled therewith by weld 42 lug 43 providing seat 44 with which may engage bolt 45. This bolt 45 is located in housing 46 provided with compartment 47. In this compartment 47 brackets 48, 49, provide guides for the bolt 45. Pin 50 in this bolt 45 is abutted by compression helical spring 51 about the bolt, which spring 51 as abutting the bracket 49 tends normally to thrust this bolt 45 outward from the housing 46, thereby to engage the seat 44, or in the instance that the door 9 be open and such door 35 is swung toward closed position, to have cam face 52 of the lug 43 ride against cam face 53 of the bolt to effect retracting of the bolt as the door is moving into the closure 8 with automatic locking as the door 9 is fully seated. This bolt 45 has link 40 connection 54 with core 55 extending into solenoid 56 mounted by bracket 57 in the compartment 47. In this compartment 47 is lock box 58. From exterior of the jamb or plate 7 there protrudes spindle 59 of combination lock having 45 tumblers 60. From manipulation of this spindle pawl 61 (Fig. 6) may enter seat 62 and effect withdrawing of bolt 63 against the action of spring 64, thereby to close switch 65. Power supply lines 66, 67, may at fitting 68 pass through the jamb 7. This line 66 is shown as having connection past the switch 65 to line 69 extending to terminal 70 and into housing 71 to act through winding 72 for urging plunger 73 against fluid resistance or dash pot at chamber 74 having a

55

controllable time leakage. A circuit from the coil or solenoid 72 extends to terminal 75 and thence by line 76 to the line 67. As there is elapsing of the time in the dash pot control, the plunger 73 has attained the lift or thrown position effective at switch 77 to connect from the line 76 through terminal 78 and line 79 to solenoid winding 56, thereby energizing the core 55 for withdrawing the bolt 45 from locking position.

10 This winding 56 has line 80 therefrom to the line 66 in completing the circuit. Any operation of the spindle 59 to shift the pawl 61 so that the switch 65 is opened after the starting of this delayed operation for the dash pot 74 re-cycles or 15 means a starting over of the dash pot operation to require a delay as initially before the switch 77 is closed to effect energizing of the winding 56. It is thus seen that if the dash pot device 74 have a delay of say fifteen minutes, at the end 20 of twelve minutes any throwing of the spindle 59 will, in opening the switch 65, return the switch 77 to its initial position and as the pawl may be again operated to close at switch 65, there is the delay for the initial setting of say fifteen minutes 25 to be added to the twelve minute or other period.

Should there be desire that control operation for access through the lock by operation of the spindle 59 as occurring say at the instance of one unauthorized, switch 81 may connect line 82 from 30 the line 69 to remote alarm 83, circuit from which is completed by line 84 to the line 76.

No meddling with the electric circuit, even with the door 8 open interferes with the locking effectiveness if the door be thereafter closed. Likewise, any meddling with the circuit with the door closed only increases the safeguarding effected by the electrical devices herein disclosed.

The front opening 6 of the general safe structure herein is shown (Fig. 11) as having closure 40 85 to form a rectangular door mounted by hinges 86 at jamb 87. Handle 88 through the door is rockable and has frangible pin connection 89 with arm 90 having slot 91 in which pin 92 is operable by rocking the handle 88. The arm 90 is effective 45 through the pin 92, causing bar 93 to move with bolts 94, 95, in slide ways of guides 96 into and out of locking position for the door. There is thus shown herein provision of a plurality of bolts for locking the door. The bolts in this instance are 50 shown only at the side remote from the hinges instead of at the hinge side also. At the hinge side, fixed lugs 97 swing back of the jamb adjacent the hinges 86 and thus cooperate in retaining the closed door in the opening 6.

55 Electric fitting 98 in the door provides current connection for electric current supply by way of line 99 to switch 65 as operable by combination lock spindle 59. At closed position for this switch 65, current may flow by line 69 direct to housing 60 71 of the dash pot re-cycling device. As this device is effective, coil 56 is energized to pull core 55 connected to withdraw bolt 45 against the resistance of spring 51. As thus withdrawn, this bolt 45 clears the inner end of primary locking 65 bolt 95 and thus allows manipulation of the handle 88 to effect unlocking of the door 85. At this unlocked position of the door 85 a shifting of the lock spindle 59 would at once effect a re-cycling or locking action tendency for this bolt 70 45. However, with the door open and the bolt 95 withdrawn, this bolt 45 merely rests on the bolt 95.

75 It thus happens that any closure of the door 35 with locking of the bolt 95 into locking position, at once causes a sliding of the bolt 45 into

holding position requiring time delay for opening. In the event of any shifting of the spindle 59 during the running of such time, there is added to this cycling a full new cycle of delay. This switch 65 instead of being operated by the spindle 59 may 5 be operated by key lock 100. Any attempt to force the handle 88, ruptures the connection 89 to preclude unlocking. Pin 89' limits the normal angular throw of the handle 88.

What is claimed and it is desired to secure by 10 Letters Patent is:

1. In a lock for a repository, a bolt, a bolt operating circuit, an electro-magnet for operating said bolt, a switch in the bolt operating circuit, a switch operating circuit having time-delayed electrical actuating means therein for operating said switch including resetting mechanism responsive to failure of current in the switch operating circuit, and a lock controlled switch in the switch operating circuit, the closing of which will initiate 20 the operation of said time-delayed electrical actuating means to complete the bolt operating circuit and the opening of the lock controlled switch will permit the resetting of the time delayed electrical means for further operation. 25

2. In a lock for a repository, a bolt, a bolt operating circuit, an electro-magnet for operating said bolt, a switch in the bolt operating circuit, a switch operating circuit having time-delayed electrical means therein for operating said switch including 30 a dashpot, resetting mechanism responsive to failure of current in the switch operating circuit, and a lock controlled switch in the switch operating circuit, the closing of which will initiate the operation of said electrical means as controlled by said dashpot to complete the bolt operating circuit and the opening of the lock controlled switch will permit the resetting of the electrical means for further operation. 35

3. In a lock for a repository, a bolt, a bolt operating circuit, an electro-magnet for operating said bolt, a first switch in the bolt operating circuit, a switch operating circuit having time delayed electrical actuating means therein for operating said switch including resetting mechanism responsive to failure of current in the switch operating circuit, and a lock controlled second switch in the switch operating circuit, the closing of which will initiate the operation of said time-delayed electrical actuating means to complete the 45 bolt operating circuit and the opening of the lock controlled second switch will permit the resetting of the time delayed electrical means for further operation, said first switch embodying a shiftable plunger, there being control means normally retarding the plunger against one direction of movement. 50

4. In a lock for a repository, a bolt, a bolt operating circuit, an electro-magnet for operating said bolt, a first switch in the bolt operating circuit, a 60 switch operating circuit having in said circuit time-delayed electrical actuating means, said electrical actuating means being effective for operating said first switch in one direction, time-delay means opposing said actuating means, resetting mechanism for the switch effective independent of opposition from the time-delay means and responsive to failure of current in the switch operating circuit, and a lock controlled second switch 65 in the switch operating circuit, the closing of which will initiate the operation of said time-delayed electrical actuating means to complete the bolt operating circuit and the opening of the lock controlled second switch will permit the resetting 70 75

of the time delayed electrical means for further operation.

5. In a lock for a repository, a bolt, there being normal actuating means for the bolt toward locking position, a bolt operating circuit, an electro-magnet for operating said bolt oppositely to said normal actuating means to shift the bolt to unlocking position, a first switch in the bolt operating circuit, a switch operating circuit having time-delayed electro-magnetic actuating means therein for operating said switch including resetting mechanism responsive to failure of current in the switch operating circuit, and a lock controlled second switch in the switch operating circuit, the closing of which will initiate the operation of said time-delayed electro-magnetic actuating means to complete the bolt operating circuit and the opening of the lock controlled second switch will permit the resetting of the time delayed electro-magnetic means for further operation, said bolt operating electro-magnet being controllable from said second switch at unlocked open position of the repository to leave the bolt free at all times to be thrown into locked position by said normal actuating means.

6. In a lock for a repository, a bolt, a bolt operating circuit, an electro-magnet for operating said bolt, a switch in the bolt operating circuit, a switch operating circuit having time-delayed electro-magnetic actuating means therein for operating said switch including resetting mechanism responsive to failure of current in the switch operating circuit, and a lock controlled switch in the switch operating circuit, the closing of which will initiate the operation of said time-delayed electro-magnetic actuating means to complete the bolt operating circuit and the opening of the lock controlled switch will permit the resetting of the time delayed electro-

magnetic means for further operation, said lock controlled switch embodying actuating means therefor comprising a spindle and actuating means for the lock control switch embodying a pawl shiftable by operation of the spindle.

7. In a lock for a repository, a bolt, a bolt operating circuit, an electro-magnet for operating said bolt, a switch in the bolt operating circuit, a switch operating circuit having time-delayed electro-magnetic actuating means therein for operating said switch including manually adjustable time delayed operating elements and resetting mechanism responsive to failure of current in the switch operating circuit, and a lock controlled switch in the switch operating circuit, the closing of which will initiate the operation of said time-delayed electro-magnetic actuating means to complete the bolt operating circuit and the opening of the lock controlled switch will permit the resetting of the time delayed electro-

20

means for further operation.

8. In a lock for a repository, a bolt, a bolt operating circuit, an electro-magnet for operating said bolt, a switch in the bolt operating circuit, a switch operating circuit having time-delayed electro-magnetic actuating means therein for operating said switch including resetting mechanism responsive to failure of current in the switch operating circuit, and a lock controlled switch in the switch operating circuit, the closing of which will initiate the operation of said time-delayed electro-magnetic actuating means to complete the bolt operating circuit and the opening of the lock controlled switch will permit the resetting of the time delayed electro-magnetic means for further operation, there being electrical connecting means between said circuits placing said switches in parallel.

CHARLES F. MEILINK.
